HUMIDIFYING APPARATUS

George R. Siefken, New York, N. Y.

Application April 5, 1943, Serial No. 481,861

7 Claims. (Cl. 261—104)

This invention relates to humidifiers, such as are commonly employed in association with radiators and like heating devices for introducing moisture into the atmosphere of a room, and is concerned more particularly with a novel humidifier which is effective in operation, inexpensive to construct, and easy to maintain in proper working order. The new humidifier may take various forms and, since it may be used to especial advantage in connection with a steam or similar radiator, a construction suitable for that purpose will be illustrated and described in detail for purposes of explanation.

In my co-pending application Serial No. 375,773, filed January 24, 1941, now Patent No. 2,323,158 dated June 29, 1943, I disclosed a humidifier which includes a vessel for liquid, a humidifying unit made up of a plurality of plates of absorbent material having portions entering the liquid in the vessel, and a cover. The construction of that humidifier is such that air rising from the radiator passes between the absorbent plates in a generally vertical direction, taking up moisture from the plates and escaping through openings in the top of the cover. In the humidifying unit of the prior humidifier, the plates of the absorbent material are mounted on one or more rods threaded through the plates and spacers are provided for holding the plates separated.

In my work with the humidifier of the co-pending application, I have found that improved results are obtained by so forming the device that the flow of air between the moist plates is in a horizontal direction, and the humidifier of the present application is constructed to insure such air flow. Also, in the new humidifier, the rear wall of the vessel, which ordinarily lies close to a wall of the room in which the device is used, is shaped to form a constriction between the wall of the vessel and the wall of the room and the jet action of the air flowing upward through the constriction improves the horizontal flow of air through the device above the constriction.

The humidifying unit employed in the new humidifier comprises a series of plates of absorbent material mounted face to face on one or more rods and held apart by spacers which may conveniently be mounted on the rods and are preferably made of absorbent material. The spacers insure that the plates, when wet, will not warp into contact and thus reduce the total surface area of the unit, and they may take vari-

ous forms, certain of which offer little resistance to air flow.

For a better understanding of the invention, reference may be made to the accompanying drawing in which

Fig. 1 is a vertical longitudinal sectional view of the new humidifier, with one of the humidifying units removed;

Fig. 2 is a transverse sectional view of the new humidifier;

Fig. 3 is a similar view of a slightly modified construction;

Fig. 4 is a sectional view on the line 4—4 of Fig. 2;

Fig. 5 is a view in perspective of a spacer employed in the humidifying unit;

Fig. 6 is a view similar to Fig. 4 showing another spacer construction;

Fig. 7 is a front elevational view of one of the absorbent plates used in the humidifying unit and illustrates a modified form of spacer;

Fig. 8 is a vertical sectional view of the plate shown in Fig. 7; and

Fig. 9 is a sectional view on the line 9—9 of Fig. 2.

In the drawing, the new humidifier is illustrated as including a vessel 10 of any suitable material and preferably metal, and this vessel is of any selected dimensions. Ordinarily the humidifier will be placed on top of a radiator 11, in which event, the vessel will be of about the width of the radiator sections and of sufficient length to cover a substantial portion of the length of the radiator. The vessel is provided with extensions 12 across its ends at the lower edges thereof and on these extensions rests a cover 13. This cover includes a top 14 and a vertical front wall 15 and, when the cover is in proper position, the front wall is spaced from the corresponding wall of the vessel so as to provide a vertical passage 16 for entrance of air rising from the radiator. The air flows transversely over the top of the vessel and out through the open rear end of the cover, as indicated at 17.

The back wall of the vessel may be provided with an extension or lip 18 projecting rearwardly toward the wall 19 of the room, or else the back wall may be inclined toward the wall 19, as indicated at 18a (Fig. 3). With either arrangement, a constriction is formed between the vessel and wall 19. Air rising from the radiator and flowing along the wall 19 passes through 55 the constriction. The effect of this constriction

is to produce a jet action which tends to increase horizontal flow over the top of the vessel.

Mounted in the vessel are one or more humidifying units and each such unit consists of a plurality of plates 20 of absorbent material. A suitable material for the purpose is a good grade of blotting paper and, in the construction disclosed, the units are of square shape, although other shapes may be employed. The units are mounted face to face in spaced relation on one or more rods 21, and in the construction illustrated in Figs. 2 and 3, there are three such rods 21 extending through the series of plates. Nuts 22 are threaded on the ends of each rod to prevent the units from being displaced and the top rods extend outwardly beyond the end units and their projecting ends are received in supports of any suitable form. In the humidifier shown, there are single supports 23 at the ends of the units and a double support 24 between the units. The supports are pieces of wood seated in the vessel and held in place in any suitable manner, as by ribs secured to the wall of the vessel or by the dovetail construction indicated at 25 in Fig. 9. At its top, each support has recesses in which the portions of the rods projecting beyond the end plates of the unit are seated. Preferably, one of the end supports 23 is spaced from the adjacent end wall of the vessel to provide room for a float valve for controlling the supply of liquid which the vessel is to contain.

In order to keep the plates properly spaced on the rods, spacers are employed between adjacent plates. These spacers may be secured to or form part of the plates themselves and when separate spacers are used, they are preferably threaded on the rods. The spacers are preferably of absorbent material, so as to provide additional humidifying surface and the spacers illustrated as mounted on the top rods in Fig. 2 are square, while the spacers mounted on the lower rods are rectangular. In all cases, the spacers used separate the adjacent plates at a number of points and prevent the plates, when wet, from warping into contact and thus cutting down the effective humidifying area.

As it is desirable to have the spacers contact with adjacent plates over a considerable area, the spacers, if made of solid material, would reduce the area of the passages between the plates through which the air flows. It is, accordingly, desirable to form the spacers so that they do not greatly interfere with the air flow and, for that purpose, the spacers may be made of U-section, as illustrated at 26 in Fig. 5. Such spacers are mounted on the rods, so that the passage between the legs of the U is horizontal, with the result that the air can flow between the legs. Instead of using separate spacers, a portion 20a at the top of each plate 20 may be bent laterally and then downwardly to lie against the opposed face of the adjacent plate and hold the plates separated.

Another type of spacer, which has proven satisfactory, is shown in Figs. 7 and 8. The absorbent plate 27, shown in those figures, forms part of a unit in which four rods 28 are used, the rods extending through the plates near the corners thereof. The spacer 29 is made of corrugated material and it is of such length as to be threaded on two rods and preferably rods lying one above the other. The corrugations of the spacer extend horizontally, so that the spacer engages adjacent plates at a number of points between the rods and defines a plurality of hori-

zontal passages through which air may flow. The spacers may be made of a high grade blotting paper, like the plates 20, or of any other suitable material. If they are made of blotting paper, they provide additional humidifying surface.

It will be seen that the spacers of all three types are formed of sheet material and have a portion in face to face contact with at least one of the absorbent plates over a considerable area. Also that part of each spacer that bridges the space between the adjacent plates presents its edge, when viewed along a horizontal line parallel to the planes of the adjacent plates. With this arrangement, the spacers may make contact with the adjacent plates over substantial areas, which is desirable to prevent warping and distortion of the plates, and at the same time the spacers do not present any substantial obstruction to the flow of air horizontally between the plates. If the spacers were cylindrical, for example, the portions bridging the space between the plates would offer considerable obstruction to the flow of air between plates if the cylinders were of a diameter sufficient to provide the desired contact at the ends with the plates. With the construction disclosed, the spacers provide the support to the plates over the desired areas, but do not offer a corresponding obstruction to air flow.

With the construction described, the air flowing upward along the front of the radiator enters the passage 16 within the cover and then flows horizontally through the spaces between adjacent moist plates to escape out through the rear end of the cover and flow upwardly along the wall 19. It has been found that an improved air flow is obtained, when the air flowing across the faces of the moist plates, travels in a horizontal direction and the jet action resulting from the use of the constriction in the passage between the rear wall of the vessel and the wall 19 assists in such flow.

During the use of the device, dust and dirt particles are likely to collect on the moist plates, so that from time to time, it is necessary to clean them. For this purpose, the cover of the device is lifted off and the units removed and washed. By making use of two short units instead of one long unit, the handling of the units for washing is much simplified.

While absorbent plates made of porous material, such as blotting paper, are satisfactory in their humidifying action, it has been found that, if these plates are not held in proper relation to one another, the heating of the plates, while they are wet, by the warm air flowing between them is likely to cause the plates to warp. Such warping may restrict the air flow in the narrow passages between the plates and also, if adjacent plates warp into contact, there is a loss of humidifying surface. By the provision of the spacers above described, such warping of the plates is avoided and, as the spacers are of absorbent material, their outer surfaces act as humidifying surface. Also, by forming the spacers of U-shape or of corrugated material, they perform their spacing function satisfactorily and, at the same time, do not cut down the cross-sectional area of the air passages between the plates.

I claim:

1. In a humidifier which includes a vessel for liquid, a humidifying unit which comprises a plurality of spaced plates of absorbent material lying face to face and having portions entering the liquid in the vessel, rods extending through

the plates, means on the rods for holding the plates thereon, and spacers of absorbent material between adjacent plates to hold them separated, the spacers being of U-section and having a portion bridging the space between the plates and leg portions lying in face to face contact with the plates over substantial areas.

2. In a humidifier adapted to be disposed above a radiator adjacent a wall and including a vessel for liquid, a cover constructed to direct flow of air in a horizontal direction only over the top of the vessel and toward the wall, a plurality of self-sustaining plates of absorbent material lying face to face with their planes parallel to the direction of air flow, the plates having portions entering the liquid in the vessel and other portions above the vessel in the path of the flowing air, means extending through the plates for holding them together, form retaining spacers between adjacent plates for holding them separated from one another and means on the vessel cooperating with said wall to form a constriction for air flowing upwardly along the wall between the vessel and the wall, the improvement in which the spacers between adjacent plates are of absorbent material to provide additional humidifying surface.

3. In a humidifier adapted to be disposed above a radiator adjacent a wall and including a vessel for liquid, a cover constructed to direct flow of air in a horizontal direction only over the top of the vessel and toward the wall, a plurality of self-sustaining plates of absorbent material lying face to face with their planes parallel to the direction of air flow, the plates having portions entering the liquid in the vessel and other portions above the vessel in the path of the flowing air, means extending through the plates for holding them together, form-retaining spacers between adjacent plates for holding them from one another, and means on the vessel cooperating with said wall to form a constriction for air flowing upwardly along the wall between the vessel and the wall; the improvement in which the spacers between adjacent plates are of absorbent material to provide additional humidifying surface, and have portions extending horizontally from one plate to the next and at least one vertical portion lying in face to face contact with the face of one of the adjacent plates.

4. In a humidifier adapted to be disposed above a radiator adjacent a wall and including a vessel for liquid, a cover constructed to direct flow of air in a horizontal direction only over the top of the vessel and toward the wall, a plurality of self-sustaining plates of absorbent material lying face to face with their planes parallel to the direction of air flow, the plates having portions entering the liquid in the vessel and other portions above the vessel in the path of the flowing air, means extending through the plates for holding them together, form-retaining spacers between adjacent plates for holding them separated from one another and means on the vessel cooperating with said wall to form a constriction for air flowing upwardly along the wall between the vessel and the wall; the improvement in which the spacers between adjacent plates are of absorbent material to provide additional humidifying surface, and have portions extending

horizontally between a pair of plates and vertical portions lying in face to face contact with the faces of adjacent plates.

5. In a humidifier adapted to be disposed above a radiator adjacent a wall and including a vessel for liquid, a cover constructed to direct flow of air in a horizontal direction only over the top of the vessel and toward the wall, a plurality of self-sustaining plates of absorbent material lying face to face with their planes parallel to the direction of air flow, the plates having portions entering the liquid in the vessel and other portions above the vessel in the path of the flowing air, means extending through the plates for holding them together, form-retaining spacers between adjacent plates for holding them separated from one another and means on the vessel cooperating with said wall to form a constriction for air flowing upwardly along the wall between the vessel and the wall; the improvement in which the spacers between adjacent plates are of absorbent material to provide additional humidifying surface and are corrugated and have the corrugations extending horizontally.

6. In a humidifier adapted to be disposed above a radiator adjacent a wall and including a vessel for liquid, a cover constructed to direct flow of air in a horizontal direction only over the top of the vessel and toward the wall, a plurality of self-sustaining plates of absorbent material lying face to face with their planes parallel to the direction of air flow, the plates having portions entering the liquid in the vessel and other portions above the vessel in the path of the flowing air, means extending through the plates for holding them together, form-retaining spacers between adjacent plates for holding them from one another, and means on the vessel cooperating with said wall to form a constriction for air flowing upwardly along the wall between the vessel and the wall; the improvement in which the spacers are portions integral with the upper edge of the plates of absorbent material and extend toward an adjacent plate and in contact therewith.

7. In a humidifier adapted to be disposed above a radiator adjacent a wall and including a vessel for liquid, a cover constructed to direct flow of air in a horizontal direction only over the top of the vessel and toward the wall, a plurality of self-sustaining plates of absorbent material lying face to face with their planes parallel to the direction of air flow, the plates having portions entering the liquid in the vessel and other portions above the vessel in the path of the flowing air, means extending through the plates for holding them together, form-retaining spacers between adjacent plates for holding them from one another, and means on the vessel cooperating with said wall to form a constriction for air flowing upwardly along the wall between the vessel and the wall; the improvement in which each spacer comprises a portion integral with the upper edge of one plate and extending towards an adjacent plate and another portion integral with said first portion which extends parallel to the plane of said adjacent plate and in face to face contact therewith.

GEORGE R. SIEFKEN.
